William H. Stevens, Inventor
By his Attorney
Frank J. Neat

UNITED STATES PATENT OFFICE.

WILLIAM H. STEVENS, OF NEW YORK, N. Y.

GARTER.

1,313,923.

Specification of Letters Patent. Patented Aug. 26, 1919.

Original application filed July 17, 1917, Serial No. 180,990. Divided and this application filed September 26, 1918. Serial No. 255,780.

To all whom it may concern:

Be it known that I, WILLIAM H. STEVENS, a subject of the King of Great Britain, residing at New York, in the county of New 5 York and State of New York, have invented certain new and useful Improvements in Garters, of which the following is a specification.

This application is a division of my application Serial No. 180,990 filed July 17th, 10 1917.

The invention relates to improvements in garters, and one of the objects is to provide an attaching member for garters of such 15 construction that it will securely hold the fabric of the stocking or garment, and without danger of tearing. The clasp is preferably made of one piece of material and provides means for effecting a resilient grip, 20 and is characterized by a construction and relation to the garter such that it may be readily manipulated for gripping and releasing the stocking or garment.

Another object is to provide an arrangement of parts such that when the device is in gripping position the stocking or other garment will be between the gripping member 25 of the garter and the skin of the wearer.

Other objects and aims of the invention, 30 more or less broad than those stated above, together with the advantages inherent, will be in part obvious and in part specifically referred to in the course of the following description of the elements, combinations, 35 arrangements of parts, and applications of principles constituting the invention; and the scope of protection contemplated will appear from the claims.

In the accompanying drawings, which are 40 to be taken as part of this specification, and in which I have shown merely a preferred form of embodiment of the invention, Figure 1 is an elevation illustrating part of a garter provided with a form of attaching 45 member embodying my invention and illustrating its connection to the garter pad as in use; and Fig. 2 is a view similar to Fig. 1 illustrating another position of the attaching member.

Referring to the numerals on the drawing, 50 3 indicates the garter pad of a leg garter, at the middle lower portion of which is provided a loop 4, in which slides a frame 5 comprising a cut-out 6 diminishing into a 55 slot 7, this construction providing a resilient

tongue 8, between which and the adjacent edge of the frame 5 the gripping action is effected. The cut-out portion 6 serves for the introduction of a bight 9 of the stocking or garment, which is then brought into position within the slot 7, either by moving the frame or by moving the material to be gripped. The garter pad extends downwardly well beyond the loop 4, so that the frame 5 overlies the end of the pad. Within 60 the loop 4 the frame 5 may be turned, by sliding it to the right or to the left, to assume the positions shown in full and dotted lines respectively in Fig. 1.

With the parts in the dotted line position 70 of Fig. 1, with the cut-out 6 at the top, corresponding to the showing in Fig. 2, a bight 9 of the stocking or garment is pulled through the cut-out 6 and held, the while the frame 5 is turned to the full line position 75 of Fig. 1. The result of this is to engage the stocking or garment firmly within the slot 7, along with the forward portion of the loop 4, and the stocking will be between the frame 5 and the end of the pad, as indicated in Fig. 1, so that the frame 5 cannot touch the skin. This is particularly advantageous in cases where the frame is made of metal, and has the further effect of diminishing the friction exercised upon the 80 stocking or garment by the edges of the gripping slot. Instead of moving the frame to the full line position of Fig. 1, the stocking might be gripped within the slot 7; and then the frame turned to the position where 90 the cut-out 6 is at the top and the slot 7 at the bottom. This would have the effect of giving the garter a little longer reach.

It will be understood that the attaching member may be made of various materials, 95 metal or celluloid or the like, but it is essential that the self-contained spring gripping member constituted by the tongue 8 co-operating with the adjacent edge of the frame should be resilient, whether inherently or by 100 reason of its conformation. Of course care should be taken to have the gripping edges in every case rounded or smooth so as to avoid tearing of the garment.

Inasmuch as many changes could be made 105 in the above construction, and many apparently widely different embodiments of my invention could be made without departing from the scope thereof, it is intended that all matter contained in the above de- 110

scription or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might 10 be said to fall therebetween.

I claim:

1. In a device of the kind described, a pad having a downward extension, a loop upon the pad above the end of the downward extension and an attaching member comprising

ing a closed frame slidable in the loop and having a cut-out portion diminishing into a recurved slot, substantially as and for the purpose set forth.

2. In a device of the kind described, a pad 20 having a downward extension, a loop upon the pad above the end of the downward extension and an attaching member comprising a closed frame slidable and revoluble in the loop and having a cut-out portion 25 diminishing into a recurved slot, substantially as and for the purpose set forth.

In testimony whereof I affix my signature.

WILLIAM H. STEVENS.
